UNITED STATES PATENT OFFICE.

FRANK E. JONES, OF PAWTUCKET, RHODE ISLAND, ASSIGNOR TO HEMPHILL COMPANY, OF CENTRAL FALLS, RHODE ISLAND, A CORPORATION OF MASSACHUSETTS.

YARN-CONTROLLING MECHANISM FOR SPRING-NEEDLE KNITTING MACHINES.

Application filed April 18, 1922. Serial No. 554,842.

To all whom it may concern:

Be it known that I, FRANK E. JONES, a citizen of the United States, and a resident of Pawtucket, in the county of Providence 5 and State of Rhode Island, have invented an Improvement in Yarn-Controlling Mechanism for Spring-Needle Knitting Machines, of which the following description, in connection with the accompanying 10 drawings, is a specification, like characters on the drawings representing like parts.

This invention relates to yarn controlling mechanism for knitting machines, and particularly to such mechanism for spring 15 needle knitting machines.

In order that the principle of the invention may be readily understood, I have disclosed a single embodiment thereof in the accompanying drawings, wherein—

20 Fig. 1 is a plan view of a portion of a circular knitting machine having my invention applied thereto;

Fig. 2 is a side elevation of the structure shown in Fig. 1;

25 Fig. 3 is a front elevation looking from the right of the sheet in Fig. 1, with parts in vertical section;

Fig. 4 is a detail mainly in vertical section, representing the upper part of a 30 needle, a presser, and a web holder cooperating therewith;

Fig. 5 is a side elevation of a part of one of the needles, and the web holder pertaining thereto;

35 Fig. 6 is a somewhat diagrammatic representation of certain of the needles as positioned in rotary knitting;

Fig. 7 is a similar view of the parts as positioned in reciprocating knitting when 40 the needles are moving in the direction opposite to that in which they moved in rotary knitting;

Fig. 8 is a plan view, somewhat diagrammatic, showing the yarn controlling 45 means and the position of the thread with respect thereto, in rotary work; and

Fig. 9 is a similar view, but showing the position of the thread in reciprocating work (the needles moving in the direction 50 opposite to that in rotary work).

My invention relates particularly to means for controlling the in-feeding yarn and more especially to means for controlling the 55 yarn which is fed to spring needle knitting machines. I have chosen to represent my

invention as applied to a rotary knitting machine, but it is not limited thereto although the invention is of peculiar importance in a spring needle knitting machine of the circular type, and more especially in a 60 spring needle knitting machine, wherein sinkers are not employed to sink the yarn between the needles, the web holders, all as clearly appears in my Patent No. 1,430,814, dated October 3, 1922. 65

The invention is represented as applied to a circular knitting machine of the type known as the Banner machine and disclosed in the Hemphill Patent No. 933,443, dated September 7, 1909. The needles employed 70 in the disclosed machine are arranged in a circular series, and are of the usual spring beard type, as shown in Figs. 1, 4, 5, 8 and 9, at 1, the stems 2 of the needles being desirably reduced or tapered to form thin 75 pointed strips which are bent to form the beards 5 terminating in points 6. The needles are provided with the usual or other knitting butts, which cooperate with appropriate knitting cams, certain of which are 80 indicated at 7 to produce the knitting wave in circular knitting or knitting waves in reciprocating knitting according to the direction of movement of the knitting mechanism. 85

The invention is principally concerned with that type of machine wherein the yarn is laid against the needle stems or shanks directly and without sinking between said shanks and to this end there are provided appropriate yarn guides herein shown as five in number at 8, 9, 10, 11, 12 in Figs. 1 and 2, and pivoted at 13 to a support 14, which in the disclosed embodiment of the invention has the general form of a half ring with a lateral projection and is itself pivoted at 15 to an upright post 16 shown in Fig. 2, the construction being such that the support or member 14 may be swung back out of the way for any purpose, as for 90 affording access to the needles. 95

The said yarn guides are arranged to be moved into and out of operation in any appropriate manner common to hosiery knitting machines, and in view of the fact that all operate in substantially the same manner, it is unnecessary to illustrate the same in detail further than is done in Figs. 1, 2 and 3, it being understood that the active yarn guide occupies a horizontal pos- 100 105 110

tion as indicated in Fig. 3, the inactive guides being moved upwardly automatically so that their yarns or threads are not delivered to the needles. When a yarn guide is in its operative position as shown in Fig. 3, the end from which the yarn is fed is preferably in close proximity to the outer faces of the needle shanks, so that the yarn which leads therefrom into the fabric will lie closely against the outer faces of said needle shanks, whereby I dispense with sinkers or other means for depressing the needles to insure the yarn between the needles passing the same without splitting the fibres thereof, as said beards descend to their pressers in passing toward the knitting point.

In machines of the character shown herein, it is common to employ devices termed web holders which are arranged between the needles and function to engage the fabric or web that has been previously formed, so as to prevent the old loops whereby said web is suspended from the needles, from working up on said needles and interfering with the formation of the new stitches or loops. This is of particular importance in spring needle knitting machines because of the fact that the space between the old loop and the new in-feeding yarn is much less than in latch needle machines and should said loops of in-feeding yarn be improperly spaced, there is likelihood of the beards of the needles being depressed at the wrong point, in which case the yarn would be split or there would be failure properly to separate the old loop from the new yarn.

Located in front of each needle is a beard depressor 17 of any desired type and such for example as that shown in my said Patent No. 1,430,814.

It is desirable that the point 6 of the needle beard should be substantially even with or past the lower edge of the yarn before depressing of the beard takes place or has progressed far enough to cause the points of said beards to cut or separate the strands of the yarn. It is therefore a function of the web holders heretofore referred to, and one of which is indicated at 18, to assist in depressing the web in the vicinity of and preferably at the needle, the point of whose beard is passing or has passed the in-feeding yarn in its descent to its presser as it approaches the knitting point in the wave produced by the knitting cams.

The web holder 18 preferably employed is provided with a lower nib 19, the entire series whereof constitute the fabric supporting bed, and it is over such lower nibs that the yarn is drawn by the descending needles and measured for the new loops. Each web holder also has an upper nib 20 which together with the lower nib 19 forms a throat 21 of sufficient depth to receive and hold the

web in its depressed position it being noted that by the term "proper level" I mean at a slight distance below the points of the beards of the needles as they are positioned just before they begin to descend the slope to the casting-off point, such level being substantially indicated in Figs. 6 and 7, as that most approved in spring needle practice. The upper nib 20 is cut relatively lower than customary for various reasons fully set forth in my said Patent No. 1,430,814.

It need merely be stated here that it is desirable that the upper nibs 20 of the web holders be not in contact with the in-feeding yarn and that said nibs leave it free and unsupported from the yarn guide to the fabric in regular knitting or from said yarn guide to the last idle needle about which it is partially wound at the beginning of each reciprocation in oscillatory knitting as the first active needle approaches the knitting point.

In order to compel the in-feeding yarn of the active yarn finger to feed directly to the needles as soon as said yarn finger is thrown into action and in order to hold the yarn against the shanks of the needles at the proper level below the points of the beards thereof, I have provided mechanism, the disclosed embodiment of which is as follows:

The support 14 is provided with a vertical face 22 at one end of the half circle, as most clearly shown in Figs. 1 and 3. Against said vertical face I secure, preferably adjustably, a member indicated generally at 23 and having a body portion 24 provided with laterally extending slots 25 for the reception of screws 26 by which the member is secured to the vertical face 22 with capacity for in and out, adjustment. The said member 23 occupies a position which may be radial to the needle circle but which is here shown as parallel to a radius and also parallel to the yarn guides 8, 9, 10, 11, 12.

The said member is provided with means to compel the yarn of any yarn finger 8 to 12 that is thrown down into action to feed directly to the needles and not to skip any of them, such as one or more of the leading needles, as sometimes occurs when the yarn finger is first thrown down into action. For this purpose I have herein represented the body portion 24 as having an upstanding part 27 here shown as vertical and in the vertical plane of the body member 24, and desirably flared at its upper end as indicated in plan, Fig. 1 so as to direct the yarn safely downwardly. It will be evident that when the yarn guide is in operative position as shown in Fig. 3, the yarn is compelled to feed to the needles immediately at the active yarn guide, and that the leading needle or needles of the series are compelled to take the yarn.

In order to support or hold the yarn against the shanks of the needles at the

proper level below the beards thereof, the body member 24 is provided with a downwardly extending portion 28, which in turn is provided with a lateral portion 29, the shape of which as indicated most clearly in Figs. 1, 8 and 9, is such as to be nearly concentric with the needle circle, though desirably the outer end thereof is sufficiently flaring or non-concentric with the needle circle to prevent all danger of impact of the needle beards therewith or other improper engagement of parts.

Desirably the device is so set that as the support 14 is swung upwardly on its pivot 15, the part 29 just grazes or just escapes grazing the beards of the needles.

The in-feeding yarn rests upon the upper surface of the part 29 which is preferably flat as shown, and the latter is at just the proper height to support the yarn against the shanks of the needles at the proper level below the beards, it being understood, as previously stated, that the yarn is not sunk between the needles, but is supported against the circle of the needles in a manner which need not be more fully described.

Having thus described one illustrative embodiment of my invention, I desire it to be understood that although specific terms are employed, they are used in a generic and descriptive sense and not for purposes of limitation, the scope of the invention being set forth in the following claims.

Claims:

35 1. A circular, spring needle, knitting machine having a circular series of spring needles and a circular series of web holders for holding the web without supporting the in-feeding yarn or sinking it between the 40 needles, one or more yarn fingers movable into and out of operative position, and means at the outside of the needle circle cooperating with the yarn feeding finger but structurally distinct therefrom to hold the 45 yarn against the shanks of the needles at the proper level below the beards thereof at substantially the in-feeding point.

2. A circular, spring needle, knitting machine having a circular series of spring 50 needles and a circular series of web holders for holding the web without supporting the in-feeding yarn or sinking it between the needles, a yarn guide movable into and out of action, and stationary means in proximity to said yarn guide at the outside of the needle circle, and close to the shanks of the needles passing the yarn guide to hold the 55 yarn against the shanks of the needles at the proper level below the beards.

60 3. A circular, spring needle, knitting machine having a circular series of spring needles and a circular series of web holders for holding the web without supporting the in-feeding yarn or sinking it between the 65 needles, a yarn guide movable into and out

of action, and cooperating means distinct from said yarn guide substantially concentrically positioned with respect to the needles at the outside of the needle circle, and in proximity to the shanks of the needles 70 to support the in-feeding yarn below the beards thereof.

4. A circular, spring needle, knitting machine having a circular series of spring needles and a circular series of web holders 75 for holding the web without supporting the in-feeding yarn or sinking it between the needles, a yarn guide movable into and out of action, and means at the outside of the needle circle structurally distinct from said 80 yarn guide but cooperating therewith to compel the in-feeding yarn to feed directly to the needles and to hold the yarn against the shanks of the needles at the proper level below the beards thereof.

5. A knitting machine having a yarn guide movable into and out of action and means structurally distinct therefrom positioned at the outside of the needle series to compel the yarn pertaining to said yarn 90 guide to feed directly to the needles as said yarn guide is thrown into action and without permitting the yarn to skip the passing needles or the leading needles of the series.

6. A circular knitting machine having a yarn guide movable into and out of action, and means structurally distinct therefrom positioned at the outside of the needle series in close proximity to said yarn guide to compel the yarn pertaining to said guide 100 to feed directly to the needles as said yarn guide is thrown into action and without permitting the yarn to skip the passing needles or the leading needles of the series.

7. A circular knitting machine having a 105 yarn guide movable into and out of action, and means structurally distinct therefrom positioned at the outside of the needle series in close proximity to said yarn guide and to the needles to compel the yarn pertaining to 110 said guide to feed directly to the needles as said yarn guide is thrown into action and also to hold the yarn against said needles at the proper level for knitting.

8. A circular spring needle knitting machine having a yarn guide movable into and out of action and having means structurally distinct therefrom, positioned at the outside of the needle series in close proximity thereto and adjustable in and out with respect to, 115 the circle of needles to compel the yarn pertaining to said guide to feed directly to the needles from said yarn guide and to hold the yarn against the shank of the needles at the proper level below the beards.

9. A circular spring needle, knitting machine having a partial ring member at the needle circle and adapted to be turned up out of the way to permit access to the needle circle, one or more yarn guides mounted 120

1. on said member for movement into and out of action, and yarn controlling means secured to said ring member in proximity to said yarn guide or guides, said means being shaped to support or hold the yarn against the shanks of the needles at the proper level below the beards without sinking the yarn between the needles.
10. A circular spring needle, knitting machine having a partial ring member at the needle circle and adapted to be turned up out of the way to permit access to the needle circle one or more yarn guides mounted on said member for movement into and out of action, and yarn controlling means secured to said ring member in proximity to said yarn guide or guides, said means having an upstanding formation to compel the in-feeding yarn to feed directly to the needles as the yarn guide is moved down into action, and also having a formation substantially concentric with the needle circle to hold the yarn against the shanks of the needles at the proper level below the beards thereof.
11. A circular, spring needle, knitting machine having a circular series of spring needles and a circular series of web holders for holding the yarn without supporting the infeeding yarn or sinking it between the needles, one or more yarn fingers, and means at the outside of the needle circle cooperating with the yarn feeding finger or fingers, but structurally distinct therefrom, to hold the yarn against the shanks of the needles at the proper level below the beards thereof at substantially the in-feeding point.
12. A circular, spring needle, knitting machine having a circular series of spring needles and a circular series of web holders for holding the web without supporting the infeeding yarn or sinking it between the needles, one or more yarn fingers movable into and out of action, and means fixed in position during the normal operation of the machine, at the outside of the needle circle to hold the yarn against the shanks of the needles at the proper level below the beards thereof at substantially the in-feeding point.
13. A knitting machine having a yarn guide movable into and out of action, and stationary means located at the outside of the needle series to compel the yarn pertaining to said yarn guide to feed directly to the needles as said yarn guide is thrown into action and without permitting the yarn to skip the passing needles or the leading needles of the series.
14. A circular knitting machine having a yarn guide movable into and out of action, and stationary means located at the outside of the needle circle but in close proximity to said yarn guide and to the needles to compel the yarn pertaining to said guide to feed directly to the needles as said yarn guide is thrown into action and also to hold the yarn against said needles at the proper level in knitting.

In testimony whereof, I have signed my name to this specification.

FRANK E. JONES.
